UNITED STATES PATENT OFFICE.

ANNA AMILIA HOGAN, OF ELMHURST, NEW YORK.

WAIST.

1,382,358.

Specification of Letters Patent. Patented June 21, 1921.

Application filed November 8, 1919. Serial No. 336,539.

To all whom it may concern:

Be it known that I, ANNA AMILIA HOGAN, a citizen of the United States, residing at Elmhurst, in the county of Queens, Long Island, and State of New York, have invented certain new and useful Improvements in Waists, of which the following is a specification.

One object of my invention is to provide 10 an improved waist which can be used as a corset waist and as a reducing waist.

Another object is to provide a waist of the above character which is so constructed that it can be readily put on and can be 15 quickly adjusted for reducing the bust.

A further object is to so design and construct my improved waist that it will perform the above mentioned functions and will stay in place without the inclusion of any 20 elastics, hooks, buttons, reinforcing bones or stays.

A still further object is to make my improved waist of a strong and durable construction and so that it can be easily manufactured. 25

These objects, and other advantageous ends which will be described hereinafter, I attain in the following manner, reference being had to the accompanying drawing in 30 which—

Figure 1 is a picture view showing my improved waist as it appears when worn on the body, and

Fig. 2 is a view of my improved waist 35 shown in a flat state; the shoulder straps or tapes being broken to permit the waist to be flattened in the construction as illustrated.

Referring to the drawing, my improved waist includes a body portion 3 which may 40 be made of any suitable fabric, such for example as woven linen. This body portion is of a shape clearly shown in Fig. 2 and includes a central portion 4 which forms the back of the waist and has its upper 45 edge preferably recessed as shown at 5. At either side of the center 6 the upper edge of the body portion slants downwardly as shown at 7 and then outwardly substantially transverse to the central vertical center of 50 the body portion. Two extensions 9 project downwardly from the central portion 4 and at an angle away from the vertical center. Each of these extensions 9 taper downwardly and have tie strings or tapes 10 con- 55 nected at their lower ends. Each of the ex-

tensions 9 has a dart 11 formed therein and the entire body portion is preferably edged by providing a facing 12 which extends around the edge of the body portion and which may be made of the material of which 60 the major portion of the waist is constructed. Also a suitable lace edge 13 can be provided.

The darts 11 extend inwardly from the outer edge portion 14 of the extensions 9 65 and the body portion adjacent the darts 11 is provided with eyelets or holes 15. These eyelets are placed near the outer edge on each of the extensions and in the present instance, one of the eyelets 15 is directly in 70 line with the adjacent dart 11 while the other two eyelets are spaced above and below the darts 11. Two shoulder straps or tapes 16 are provided and each of these straps has one end secured adjacent the joining of the 75 edges 14 with the edges 8 and the other end secured at the uppermost part of the central portion 4 at both sides of the center, as clearly shown in Fig. 2.

The central portion 4 has two darts 17 80 formed therein at opposite sides of the center 6. Facing strips 18 extend upwardly from the bottom of the central portion 4 at angles which flare upwardly.

When the garment is put on, as shown in 85 Fig. 1, the portion 4 forms the back and the part 8 fits under the arms while the portions 9 are of such shape that they can be wrapped in an overlapped state around the waist and the tie strings 10 can be tied either in the 90 back or, if desired, can be again wound around the body and tied in the front according to the pleasure of the wearer.

A lace or drawing ribbon 19 is inserted through the eyelets 15, as shown in Fig. 1, 95 and when in position, the darts 11 will be located across the bust and when the lace is pulled the edge portions 14 of the extensions 9 adjacent their upper parts will be drawn together to reduce the bust. The 100 darts 11 also form a strong section of the body portion so that the bust can be reduced to any desired size according to the tightness or pull imparted to the draw ribbon 19. The ends of the draw ribbon may 105 be tied in a bow after the desired tension has been secured.

It is thus obvious that any desired adjustment can be secured by the means of the tie strings 10 for the general fitting of the waist 110

and in addition, the size of the bust can be varied so that the entire garment will be comfortable.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A waist including a central back portion and extensions projecting laterally from said back portion, each of said extensions having edge portions shaped to taper downwardly at converging angles when arranged on the body of the wearer whereby a front opening is produced converging downwardly from the neck and shoulders to a position adjacent the bust, said extensions below said opening being adapted to overlap each other; means for securing the extensions in their overlapped position below said opening, said edge portions of the extensions at a level above the bottom of said opening having draw string-engaging means thereon; and a draw string connected to said engaging means of each edge portion and extending across the bottom of said opening whereby said edge portions can be drawn toward each other to decrease the width of

the bottom of said opening and to place tension upon the portion of said extensions covering the bust; substantially as described.

2. A waist including a central back portion and extensions projecting laterally from said back portion, each of said extensions having edge portions shaped to taper downwardly at converging angles when arranged on the body of the wearer whereby a front opening is produced converging downwardly from the neck and shoulders to a position adjacent the bust, said extensions below said opening being adapted to overlap each other; means for securing the extensions in their overlapped position below said opening, said edge portions of the extensions at a level above the bottom of said opening having draw string-engaging means thereon; and a draw string connected to said engaging means of each edge portion and extending across the bottom of said opening whereby said edge portions can be drawn toward each other to decrease the width of the bottom of said opening and to place tension upon the portion of said extensions covering the bust, said extensions having darts formed therein positioned in alinement with the bust of the wearer; substantially as described.

In testimony whereof I have signed my name to this specification in the presence of two subscribing witnesses.

ANNA AMILIA HOGAN.
